COMBINED MOBILE LABORATORY TABLE AND CABINET UNIT

Arthur W. Carlson, Muskegon, Mich., assignor to E. H. Sheldon & Company, Muskegon, Mich., a corporation of Michigan

Filed Aug. 3, 1964, Ser. No. 81,129

Term of patent 14 years

(Cl. D16—2)

FIGURE 1 is a front perspective view of a combined mobile laboratory table and cabinet unit, showing my new design;

FIGURE 2 is a front perspective view with the front vertical panels reversed in position to show the plain side of the panels;

FIGURE 3 is a rear perspective view showing horizontal panels in forwardly-extending position;

FIGURE 4 is a view similar to FIGURE 3 but showing the horizontal panels in vertically-aligned relation;

FIGURE 5 is a front view in elevation of the structure shown in FIGURE 1;

FIGURE 6 is a side view in elevation of the structure shown in FIGURE 5 with the horizontal panels in extended position; and

FIGURE 7 is a rear view in elevation of the structure in the position shown in FIGURE 6.

I claim:

The ornamental design for a combined mobile laboratory table and cabinet unit, substantially as shown.
